(57) **CLAIM**

The ornamental design for a finger ring, as shown and described.

DESCRIPTION

FIG. 1 is a front elevational view of my new finger ring design, the rear elevational view being identical;

FIG. 2 is a left side view thereof, the right side view being identical;

FIG. 3 is a top plan view thereof;

FIG. 4 is a bottom plan view thereof;

FIG. 5 is a front elevational view of a second embodiment of FIG. 1, the rear elevational view is identical to FIG. 1; and FIG. 6 is a left side view thereof, the right side view being a mirror image thereof; and,

FIG. 7 is a top plan view thereof, the bottom plan view corresponds to FIG. 4.

The darker shaded gemstones in FIGS. 2, 4 and 5 illustrate gemstones of a contrasting color.
